SELF SERVICE UNIT FOR TESTING AND STORING ELECTRONIC TUBES

Albert Armato, Milwaukee, and Carl R. Riolo, Pewaukee,
Wis., assignors to U-Test-M Mfg. Co., Inc.

Application June 5, 1957, Serial No. 46,487

Term of patent 14 years

(Cl. D80—9)

Fig. 1

Fig. 2

Fig. 3

Fig. 1 is a perspective view of the front and one side of the self service unit for testing and storing electronic tubes showing our new design, the rear being substantially plain;

Fig. 2 is a front elevational view of Fig. 1; and

Fig. 3 is a side elevational view thereof.

We claim:

The ornamental design for a self service unit for testing and storing electronic tubes, as shown and described.
